US00D584591S

(12) **United States Design Patent**
Tano et al.

(10) **Patent No.:** US D584,591 S
(45) **Date of Patent:** ** Jan. 13, 2009

(54) **POLISHING PAD**

(75) Inventors: **Hiroyuki Tano**, Chuo-ku (JP); **Hiroshi Shiho**, Chuo-ku (JP)

JP 115633 9/2002

(73) Assignee: **JSR Corporation**, Tokyo (JP)

(Continued)

(**) Term: **14 Years**

OTHER PUBLICATIONS
U.S. Appl. No. 29/295,291, filed Sep. 25, 2007, Tano, et al.

(21) Appl. No.: **29/295,292**

(Continued)

(22) Filed: **Sep. 25, 2007**

Primary Examiner—T. Chase Nelson
(74) Attorney, Agent, or Firm—Oblon, Spivak, McClelland,
Maier & Neustadt, P.C.
